DESIGN FOR A COVER FOR AN ELECTRIC CIRCUIT CONTROLLER CASING

Clifford Brooks Stevens, Milwaukee, Wis., as-
signor to Cutler-Hammer, Inc., Milwaukee,
Wis., a corporation of Delaware

Application December 18, 1937, Serial No. 73,699

Term of patent 14 years

To whom it may concern:

Be it known that I, Clifford Brooks Stevens, a citizen of the United States and a resident of Milwaukee, in the county of Milwaukee and State of Wisconsin, have invented a new, original, and ornamental Design for a Cover for an Electric Circuit Controller Casing, of which the following is a specification, reference being had to the accompanying drawing, forming part thereof.

Figure 1 is a front elevational view of a cover for an electric circuit controller casing, showing my new design, and

Fig. 2 is a sectional view on line 2—2 of Fig. 1.
I claim:

The ornamental design for a cover for an electric circuit controller casing, substantially as shown.

CLIFFORD BROOKS STEVENS.
